US00D990701S

(12) **United States Design Patent** (10) **Patent No.:** **US D990,701 S**
(45) **Date of Patent:** **** Jun. 27, 2023**

(54) **HAND-HELD ULTRAVIOLET
STERILIZATION DEVICE**

(71) Applicant: **GOLDENSUNDA TECHNOLOGY
CO., LTD.**, New Taipei (TW)

(72) Inventors: **Chi-Yao Liao**, New Taipei (TW); **Li-Li
Mao**, New Taipei (TW); **Yu-Lung

CLAIM

The ornamental design for a hand-held ultraviolet sterilization device, as shown and described.

DESCRIPTION

FIG. 1 is a perspective view of a hand-held ultraviolet sterilization device showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

1 Claim, 7 Drawing Sheets
